[57] ABSTRACT

An accessorial device for holding a helmet or the like on an autobicycle is comprised of a handle setter for holding the handle of the autobicycle on the frame thereof, a hook-shaped cover member of which root portion is pivotally connected to the handle setter so as to cover at least part of the upper surface of the handle setter while the cover member holds a loop portion of the tie band of a helmet or the like at its hook-shaped portion in association with the upper surface of the handle setter, and a locking means for locking up said cover member against the handle setter, whereby the helmet or the like is certainly held on the autobicycle not to be stolen.

FIG. 1

FIG. 2

ACCESSORIAL DEVICE FOR HOLDING A HELMET OR THE LIKE ON AN AUTOBICYCLE

BRIEF SUMMARY OF THE INVENTION

The present invention relates to an accessorial device for holding a helmet or the like on an autobicycle.

One object of the present invention is to provide an accessorial device for holding a helmet or the like on an autobicycle which a rider on the autobicycle can easily operate to connect his helmet or the like to or take it out apart from the frame of the autobicycle.

Another object of the present invention is to provide an accessorial device for holding a helmet or the like on an autobicycle having a cover member to cover at least one bolthead of bolts affixing a handle setter to the frame of the autobicycle to hold a handle therebetween so that the bolt covered with the cover member would not be screwed out from the frame, whereby a helmet or the like held by the cover member is certainly connected to the frame.

Further object of the present invention is to provide an accessorial device for holding a helmet or the like on an autobicycle which should be easily mounted on a conventional autobicycle only by substituting the handle setter thereof for the conventional one.

Further more object of the present invention is to provide an accessorial device for holding a helmet or the like on an autobicycle which enables to put a helmet over the fuel tank behind the handle of the autobicycle not to stay rain water inside the helmet in rainy weather.

BRIEF DESCRIPTION OF THE DRAWINGS

FIG. 1 is a perspective view of a device according to the present invention.

FIG. 2 is a cross-sectional side elevation view of the device shown in FIG. 1.

DETAILED DESCRIPTION

Referring to FIG. 1 and FIG. 2, therein is seen a head pipe 28 fixedly connected to a frame body 27 of an autobicycle at the front portion thereof. A front fork 1 is pivotally connected to the head pipe 28 in a conventional manner, and a handle holder 2 is fixed to a upper-most portion of the front fork 1. A handle 4 is tightly held between the handle holder 2 and a handle setter 3 positioned upon the handle holder 2 with use of several bolts 5, 6.

A hook-shaped cover 8 is pivotally connected to the upper surface of the handle setter 3 turnably around a pivot 9 at the root portion thereof. The cover 8 has a concave 10 to cover the bolthead 7 of the rear bolt 6 while the cover 8 is laid flat upon the handle setter 3, and has a transverse concave to form a holding hole 14 in association with the upper surface of the handle setter 3 with which should hold a ring member 13 connected to the tie band 12 of a helmet 11 or the like (FIG. 1). The cover 8 has also a transversely settled horizontal pin 15 inside the downwardly opened concave at the free-end portion thereof.

At the back portion of the handle setter 3, there fomed an accommodation space 16 with a bottom plate 18, to accommodate a locking mechanism 17 which is comprised of a hook member 19 turnable around a pivot 20 supported on the inner side wall of the handle setter 3, of which hook portion at the uppermost portion thereof is to engage with the pin 15, a spring 24 biasedly enforcing the hook member 19 to hold engagement with the pin 15, and a cam 23 affixed to the axle 22 of a cylinder-type lock which is to be operated with a key 21 (FIG. 1) to push the root portion of the hook member 19 against force of the spring 24 with aid of the cam 23.

The cover 8 is upwardly enforced by a spring 25 so that the cover 8 automatically turns upwards around the pivot 9 when the hook member 19 is disengaged from the pin 15.

In operation, for the purpose of holding the helmet 11 or the like, at first a rider should turn the axle 22 by using the key 21, whereupon the cam 23 acts on the hook member 19 to disengage it from the pin 15, and the cover 8 is turned upwards around the pivot 9. Then he should position the ring member 13 of the helmet 11 of the like in the holding hole 14 and thereafter push the cover 8 downwards. Consequently the hook member 19 engages again with the pin 15 with operation of the spring 24, and the cover 8 is locked against the handle setter 3 holding the helmet 11.

When the rider wants to take out the helmet 11 from the cover 8, he can turn the axle 22 to open the cover 8 by using the key 21.

I claim:

1. An accessory for safe-keeping an article on a motorcycle comprising handle holding means on said motorcycle; handle setting means attached to said handle holding means for holding tightly therebetween the center portion of a handle; a plurality of bolts for fastening said handle setting means to said handle holding means; a hook-shaped cover member connected pivotally at its base to said handle setting means so as to cover at least one bolthead of said bolts, said cover member having a recess for forming a cavity with said handle setting means to hold said article; and locking means connecting said cover member to said handle setting means for securely locking said article between said cover member and said handle setting means.

2. The accessory as defined in claim 1 including spring means connected to said cover member for urging said cover member in an upward direction.

3. The accessory as defined in claim 1 wherein said locking means comprises a pin member within said cover member; a hook-shaped lever member pivotally located in a space adjacent to said handle setting means; spring means connected to said lever member for urging said lever member against said pin member at the uppermost portion of said hook-shaped lever; cam means rotatable on an axle of a cylinder-type lock for turning said hook-shaped lever about the pivot of said lever to unlock said cover member by disengaging said hook-shaped lever from said pin member.
